HARRY WEARNE, OF RIXHEIM, GERMANY.

DESIGN FOR WALL-PAPER.

SPECIFICATION forming part of Design No. 29,655, dated November 8, 1898.

Application filed October 13, 1898. Serial No. 693,457. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion 16 of a strip of wall-paper embodying the features of my design.

The design consists in a series of striped

panels A, arranged in parallel order, the spaces between alternately-grouped striped panels being decorated by garlands of roses B and festooned bars C, adjacent to which floral figures D appear.

I claim—

The design for wall-paper herein shown and described.
